UNITED STATES PATENT OFFICE.

WILLIAM E. BLINDT, OF NEWARK, NEW JERSEY, ASSIGNOR TO JONES & WOODLAND COMPANY, A CORPORATION OF NEW JERSEY.

DESIGN FOR A FINGER RING.

60,602.

Specification for Design. Patented Mar. 14, 1922.

Application filed October 22, 1921. Serial No. 509,715. Term of patent 7 years.

To all whom it may concern:

Be it known that I, WILLIAM E. BLINDT, a citizen of the United States, residing at Newark, in the county of Essex and State of New Jersey, have invented a new, original, and ornamental Design for a Finger Ring, of which the following is a specification, reference being had to the accompanying drawings, forming a part thereof.

The invention is clearly illustrated in said accompanying drawings, in which Figure 1

is a top-plan view, and Figures 2 and 3 are the two side-edge views of my new, original and ornamental design for a finger ring.

I claim:

The ornamental design for a finger ring, as shown.

WILLIAM E. BLINDT.
